UNITED STATES PATENT OFFICE.

THOMAS LEE, OF HOME CITY, OHIO.

SILL-BRACE FOR METALLIC WINDOW-FRAMES.

No. 833,328.

Specification of Letters Patent.

Patented Oct. 18, 1908.

Application filed May 12, 1906. Serial No. 316,473.

To all whom it may concern:

Be it known that I, THOMAS LEE, a citizen of the United States, residing at Home City, Hamilton county, State of Ohio, have invented a certain new and useful Sill-Brace for Metallic Window-Frames; and I do declare the following to be a clear, full, and exact description of the invention, attention being called to the accompanying drawings, with the reference characters marked thereon, which form also a part of this specification.

This invention relates to improvements in window-frames consisting of hollow structures made of sheet metal.

Such frames are generally used in connection with fireproof or fire-retarding windows. While they possess sufficient rigidity for the intended purpose, the sills of such frames are exposed to injury in various ways and from external pressure—as, for instance, if stepped upon—when by reason of insufficient resistance they are liable to lose their shape or collapse. A usual expedient to circumvent this difficulty is to fill such sills with cement or concrete. The objections to this method are the hygroscopic properties of such material, which draws and retains moisture and does not readily dry out when so incased, all of which is detrimental to the surrounding metal. Considerable otherwise useless weight is also added, which has to be handled during manufacture, transportation, and setting up of these frames. A most potent objection is, further, that such material if drying, shrinks considerable, thus leaving the upper part of the sills unsupported, particularly at the edges, so that the most important intended function to preserve the shape, particularly at such edges, is lost; and nicks and dents result. My invention provides means which overcome these objections, are not unnecessarily heavy, and are fitted to the shape of the sills, which they fill perfectly and completely and which fit remains permanent.

In the following specification, and particularly pointed out in the claims at the end thereof, is found a full description of my invention and the construction of the same, which latter is also illustrated in the accompanying drawings, in which—

Figure 1 shows in perspective view a portion of the lower part of a hollow sheet-metal window-frame, it being the lower part of one of the upright members and a part of the adjoining sill, the latter containing the means

provided by my invention. Fig. 2 is a vertical cross-section of the sill as shown in Fig. 1. Fig. 3 is a rear view of Fig. 1.

A indicates the lower part of one of the upright members of the frame.

B is the sill shown as of conventional shape, b being the seat for the lower sash (not shown) and is usually higher and above the other part of the sill, producing an offset b'. 65

In the form of sill shown six longitudinal edges or corners result, which are liable to lose their shape unless stiffened by means which brace the sill in a manner to retain its shape. My means consist substantially of a brace C, which supports the upper side or wall of the sill by being fitted against the under side and into and against all corners of the same and being supported itself by its front side D and its rear side E. These sides D and E are fitted against front and rear walls of the sill, as best shown in Fig. 2. While my brace might also have a bottom part, such is not essential, since the bottom side b' of the sill resting generally upon a wall is not exposed in a manner to be liable to injury. 70

This sill-brace is preferably made of cast metal, a cheap grade of cast-iron being sufficient, since outside of sufficient stiffness and rigidity no other qualifications are required. 75

The thickness of this metal should therefore be limited to merely meet these requirements to save metal and to reduce weight, and

these latter requirements are further satisfied by providing openings and cut-outs at such 80

places where the absence of metal will not interfere with the principal function of the device as a brace. Thus openings c are pro- 85

vided in the upper part of the brace and cut-outs or recesses d and e in front and rear sides, 90

respectively. The resultant structure is an independent skeleton frame which is devoid 95

of all unnecessary metal and weight, but preserves wherever necessary all corners and edges intact. As to length these braces may 100

come, preferably, in units of suitable, but limited lengths, to permit building up of the required length to fill a sill, into which they are 105

shoved endwise one after the other, the sills being of course made to fit closely around the 110

braces, unless, however, a large number of sills has to be filled which are all of equal 115

length, in which case the braces may all be of one piece and fitted to the length of the par- 120

ticular sill. Another advantage of such an open-work skeleton frame is that it may be 125

readily broken crosswise, the arrangement

22

openings *d*, *c*, and *e*, transversely alined, favoring such breakage and permits making up of odd lengths. At the ends and also, if necessary, at suitable intermediate points this skeleton frame may be strengthened by transversely - extending webs. Wherever necessary such fillings may of course be also provided for the upright members of a window-frame. Where window-frames are ventilated, this filling does not interfere with such ventilation.

Having described my invention, I claim as new—

1. A brace for the hollow members of a metallic window-frame, consisting of an open-work, cast-metal skeleton frame fitted to fill such member.

2. A brace for the hollow sill of a metallic window-frame, consisting of an open-work, cast-metal, skeleton frame fitted to fill such a sill so as to sustain the corners and edges thereof.

3. A sill-brace for the hollow sills of metallic window-frames, consisting of an upper part which is fitted against the under side of the upper part of the sill and of front and rear sides which support such upper part and are fitted respectively against front and rear sides of the sill all extending from one end of the sill to the other.

4. A sill-brace for hollow sills of metallic window-frames, consisting of an upper part provided with perforations and fitted against the under side of the upper part of the sill and of front and rear sides which support such upper part and are provided with cut-outs.

In testimony whereof I hereunto affix my signature in presence of two witnesses.

THOMAS LEE.
